UNITED STATES PATENT OFFICE.

SARKIS JELALIAN, OF CRANSTON, RHODE ISLAND.

SPORTING DIRIGIBLE BALLOON.

1,137,212.

Specification of Letters Patent. Patented Apr. 27, 1915.

Application filed January 14, 1915. Serial No. 2,138.

To all whom it may concern:

Be it known that I, SARKIS JELALIAN, a citizen of the United States, residing at the city of Cranston, in the county of Providence and State of Rhode Island, have invented certain new and useful Improvements 5 in Sporting Dirigible Balloons, of which the following is a specification.

The invention relates to dirigible air 10 ships, and more particularly to that class of air-ships employing a dirigible balloon for assisting in lifting a person and embodying wings for driving said person forward.

15 The object in view is to provide means to easily permit a person to fly in the manner of a bird by the aid of the gas bag.

The invention consists of the peculiar features of construction and combination of 20 parts as hereafter described and claimed.

In describing the invention in detail, reference will be had to the accompanying sheet of drawings in which—

Figure 1 is a side elevation of the balloon 25 from which suspends a body of a person. Fig. 2 is a top view of the device as applied to the back of the person. Fig. 3 is a plan view showing the relation of the device as applied to the body of the person. Fig. 4 is a front view showing the device as strapped to the body of a person. Fig. 5 is an enlarged detail view of a rectangular back support, illustrating the folding manner of the side projecting wings.

30 Referring to the drawings, numeral 1 designates a balloon from which suspends a body of a person 3, by means of suspensions 2; with side projecting wings 4, the function of which is to react against the atmosphere to make a safe gradual downward descent whenever the gas bag collapses. 35 Means are provided also to fold said wings when desired by the operator.

Extending outwardly from the person 3 40 is a pair of bird-like wings 5, which are secured to the arms of said person by means of belts 9, and the inner ends of said wings 5 are pivoted to the upper side of the rectangular support 10 as shown in Fig. 3 and 45 in Fig. 4.

The wings 5 may be easily and freely flapped as may be desired by the person or the operator by the power of the arms, thus forcing the air directly beneath the laterally 50 projecting wings 4. Said wings 4 extend outwardly from the sides of the rectangular

support 10, said support 10 is secured to the body of the person 3, by means of straps or belts 6, as shown in Fig. 1, and in Fig. 4.

Immediately beneath the straps 6, is a 55 soft cushion 7 applied lengthwise to the body of the person 3, this cushion 7 is utilized to keep the body of the person free from pressure from said straps 6. A similar cushion is also provided in the back.

Extending from the forward end of the person 3, is an outwardly extending flat pentagonal hat 8, applied and secured to the head of said person, the purpose of this hat is to keep the head of the person in level 60 position by the aid of its outwardly extending portion.

In Fig. 5, is illustrated the folding manner of side projecting wings 4, in said figure numeral 15 designates a series of flat wing 75 supports, and near to the inner ends thereof are provided eyes which are loosely mounted on vertically arranged stationary pins 16 secured to the back support 10. The inner ends of said supports 15 having pivotal connection with a flat bar 17, said bar 17, being provided with a spring attachment 18, and a rope 19 extending forwardly from the rear end of said spring adjacent to the operator. So it is apparent that when a pull is made 80 from the free end of the rope 19, the supports 15 will have folding movement into backward position through the connection with bar 17, as shown with dotted lines in said Fig. 4.

90 Means are provided for the operator to let free his arms as far as the elbow when desired, in order to fold side projecting wings 4 when proposing to land. The gas bag 1 has an ordinary tube provided with a common valve within easy reach of the operator, to permit the escape of gas from said bag in making a descension.

95 In use the gas bag may be omitted in order that the apparatus may form a "glider," 100 in making a flight from a hill or high elevation.

The hat being provided with a pentagonal plane assists the aviator in making the forwardly ascending and descending courses, 105 by simply moving his head upward or downward, as is obvious.

From the merits of the device described, it will be seen that a person will be able to fly safely and successfully in the manner of 110 a bird.

It should be understood that the material

used for the purpose described should be light and firm, such as bamboo or other suitable material.

Thus having described my invention, what I claim as new and desire to secure by Letters Patent is:—

1. An apparatus of the character described, comprising a gas bag having means to permit the escape of gas from the latter, 10 a rectangular back support suspended from said bag and adapted to be secured to the body of the aviator, a flat outwardly extending wing portion pivoted to and projecting from each side of said support, a pair of 15 bird-like wings pivotally secured to the forward end of said support, and arm-securing straps on said wings.
2. An apparatus of the character described, comprising a gas bag having means 20 to permit the gas to escape from the latter, a rectangular support for the aviator having outwardly extending planes pivoted to and projecting from each side thereof, wings pivotally secured to the said support, forwardly of its planes, said support and said wings having straps for securing to the body 25 of the aviator.

3. An apparatus of the character described, comprising a gas bag having means to permit the escape of gas from the latter, 30 a support having outwardly extending planes pivoted to and projecting from each side thereof, flat wings pivotally secured to the forward part of said support, means for securing the said support and said wings to 35 the aviator, a hat adapted to be secured to the aviator and having a flat outwardly projecting pentagonal plane.

4. An apparatus of the character described, comprising a gas bag having means 40 to permit the escape of gas from the latter, a back-support, planes projecting from each side of the same, a movable bar, supports for said planes, each support pivoted to the said back-support and connected to the said bar, 45 and means to actuate said bar to bring the supports for said planes to a folded position.

In testimony whereof I affix my signature in presence of two witnesses.

SARKIS JELALIAN.
